WILFRED LEWIS, OF HAVERFORD, PENNSYLVANIA.

MOLDING-MACHINE VALVE MECHANISM.

1,157,406.

Specification of Letters Patent.

Patented Oct. 19, 1915.

Application filed March 13, 1915. Serial No. 14,080.

To all whom it may concern:

Be it known that I, WILFRED LEWIS, a citizen of the United States of America, residing in Haverford, in the county of Montgomery, State of Pennsylvania, have invented 5 certain new and useful Improvements in Molding-Machine Valve Mechanism, of which the following is a true and exact description, reference being had to the accompanying drawings, which form a part thereof.

My present invention consists in part in an improved valve mechanism especially adapted for use in a fluid pressure operated 15 jar molding machine, and in part in the relative construction and arrangement of the valve mechanism and the jar molding machine to which it is applied.

My invention comprises improvements 20 over the apparatus disclosed and claimed in my prior application, Serial No. 849641, filed July 8, 1914, devised with the purpose of making the valve mechanism simpler in construction and of greater inherent rapidity and positiveness of operation, and with 25 the further object of permitting a reduction in the unnecessary and undesirable clearance space in the fluid pressure operating mechanism of the jar molding machine in 30 which my invention is employed.

The various features of novelty which characterize my invention are pointed out with particularity in the claims annexed to and forming a part of this specification. 35 For a better understanding of my invention, however, and the advantages possessed by it, reference should be had to the accompanying drawings and descriptive matter in which I have illustrated and described two 40 preferred embodiments of my invention.

Of the drawings: Figure 1 is an elevation partly in section of a molding machine equipped with a preferred form of my invention; Fig. 2 is a sectional elevation on a 45 larger scale than Fig. 1, of a portion of the apparatus shown in Fig. 1; and Fig. 3 is a section through one of the valve members the section being taken on the line 3—3 of Fig. 2.

The molding machine shown in Fig. 1 is 50 of the so called shockless type, the stationary base A being formed with a cylinder space A' receiving the vertically movable, spring supported floating anvil B. The latter is formed at its upper end with a piston B' on which cylinder C' formed on the un-

der side of the mold support C works. The mold support is centrally apertured and recessed to provide a seat for the admission valve casing F. The upper end of the aperture is closed, and the valve casing F secured in place, by the head C³ detachably secured to the body of the mold support. The head C³ is provided with a lubricator C⁴ for supplying lubricating material to the 60 valve mechanism working in the valve casing F. The anvil is recessed at B² to receive the valve mechanism and provide the necessary clearance.

During the jarring operation the chamber F' in the casing F is continuously supplied with the working pressure fluid from a compressed air supply tank or other fluid pressure supply source, as by means of the flexible pipe L and the valve L' which may be a 70 three-way valve adapted to connect the chamber F' either to the fluid pressure supply source or to the atmosphere. The passage of the pressure fluid out of the chamber F' through the port F² to act between 75 the piston B' and the upper end of the cylinder C' in lifting the mold support above the anvil preparatory to collision, is controlled by a valve member G having a fluted portion G' lying within the port F² at all 80 times, and a conical valve seat engaging portion G² adapted to seat against the conical valve seat F³ under certain conditions as 85 hereinafter explained. Since practically all of the valve mechanism is located above the port F², and the latter is at the lower end 90 of the valve casing, the anvil and mold support may be, and are shown as being formed with the clearance space in the piston and cylinder connection between the mold support and anvil reduced to a practical minimum. 95

Above its valve seat engaging portion the valve G is formed with a cylindrical extension having a lower chamber G³ of large 100 diameter and a coaxial upper chamber G⁴ of smaller diameter. As shown, the chamber G⁴ is located within a sleeve member G⁵ rigidly secured to the body of the valve member G. The chamber G³ is closed at its 105 lower end except for a central opening receiving the plunger H which carries the main exhaust valve J at its lower end. The exhaust passage B³, communication between which and the chamber B² is controlled by 110 valve J, leads through the anvil B to the chamber A'. At the upper end of the plun-

ger H is a piston H' working in the chamber G⁴, and mounted on an intermediate portion of the member H is a piston I, working in the chamber G³, and movable relative to the member I between the plunger shoulder H² and the stop collar H¹³. In the construction illustrated the plunger H comprises a stem reduced at its upper end, having its reduced upper portion surrounded by the piston H' and the depending tubular stem H¹⁰ thereof, and by a sleeve member H¹¹ on which the piston I actually works. The sleeve H¹¹ and plunger stem are rigidly connected. The piston H' and sleeve H¹⁰ are axially clamped between the stem shoulder H¹² and the nut H¹⁴ threaded and pinned to the upper end of the plunger stem. The sleeve H¹¹ is larger in diameter than the unreduced portion of the plunger stem, and the tubular stem of the piston H', and its upper end forms a stop for the stop collar H¹³ which is slidingly mounted on the sleeve of the piston H' and is normally held against the sleeve H¹¹ by the spring M acting between the under side of piston H' and the flanged lower end of the sleeve H¹¹. A pin H¹⁵ is employed to prevent rotative but not axial movements of the piston I relative to the plunger H.

The plunger H is formed with an axial passage H³ in its upper portion. The passage H³ is at all times in free communication at its upper end with the inlet chamber F', and communicates at its lower end through a lateral extension with the upper horizontal branch I³¹ of a passage I³ in the piston I when the latter engages the shoulder H², and with the lateral branch at the upper end of a passage I⁴ in the piston I when the latter is in engagement with the stop collar H¹³. The lower end of an axial passage H⁴ formed in the lower portion of the plunger H is in communication at all times with the exhaust passage B³, regardless of whether the valve J is seated or not. At its upper end the passage H⁴ communicates with the lateral branch at the upper end of the passage I⁴ when the piston I engages the stop shoulder H², and communicates with the lower lateral branch I³² of the passage I³ when the piston I engages the collar H¹³. The passage I⁴ is open to the lower end of the chamber G³ at the under side of the piston I, and passage I³ is open to the upper end of the chamber G³ at the upper side of the piston I.

When the parts are in the position shown in Fig. 2, the upper end of the sleeve portion G⁵ of the valve member G engages an apertured stop plate or spider C⁵. The latter is normally held against the valve casing shoulder F¹⁴ beneath it by the powerful spring N. The purpose of the spring pressed stop plate C⁵ is to provide a stop for the upward movement of the valve mem-

ber G in its casing which will yield to prevent the valve mechanism from being crushed in case of a failure, or diminution in thickness of the usual buffer washer Z interposed between the striking surfaces of the mold support and anvil. A comparatively light spring L, acting between the lugs G¹¹ and the shoulder F⁵ of the casing F, approximately counter balances the weight of the valve body. A spring K, somewhat stronger than the spring L, but weaker than the spring N, acts between the valves G and J, and tends to hold them apart. As shown, the lower end of the spring K directly engages the flange R' at the lower end of a sleeve R surrounding the stem of the plunger H and bearing against the valve J. The upper end of the spring K actually engages the gland G¹² of the stuffing box employed to prevent leakage along the plunger H into or out of the chamber G³.

The parts are shown in Fig. 2 in the relative positions occupied when the mold support is in its lowermost position relative to the anvil. In this condition the exhaust valve J is on its seat, and the inlet valve is held in its wide open position in which the valve body G engages the abutment spider C⁵ by the spring K, and by the differential effect on the valve mechanism of the exhaust pressure in the lower end of the chamber G³ and of the supply pressure acting on both sides of the open port F'. This differential fluid pressure effect maintains the valve member G in its wide open position during the initial upward movement of the mold support.

After a predetermined upward movement of the mold support the piston I is engaged by the lower end wall of the chamber G³, and moved upward relatively to the member H, until passages H³ and I⁴ are in communication, and communication is established between passages I³ and H⁴. Since the cross sectional area of the piston I is less than the cross sectional area of the annular space in the chamber G³ surrounding the lower stem portion of the plunger H, as soon as air begins to flow through passages H³ and I⁴ into the lower end of the chamber G³, while at the same time the space above the piston I is connected through passages I³ and H⁴ to exhaust, the valve member G is moved downward and the plunger H upward, thus seating the valve member G and lifting the exhaust valve J off its seat. The valve G naturally seats before the valve J opens. On the subsequent falling movement of the mold support, the valve J first seats, and then, as the downward movement of the mold support continues, the valve member G opens under the tension of the springs K and L and the increasing pressure of the air trapped in the chamber B³. Should

these forces be insufficient, as in case of the breakage or omission of either or both the springs K and L, the positive engagement of the plunger H and valve member G, through sleeve R, will insure the opening of the inlet valve. At about the instant at which the valve G would begin to open under the action of spring K alone, the relative movement between member G and the 10 plunger H causes the piston I to shift, and connect passage I³ to H³ and passage I⁴ to H⁴, so that the resultant upward fluid pressure on the valve member G due to the low pressure prevailing in the lower end of chamber 15 G³ assists in moving the valve member G into its wide open position. A characteristic feature of this form of valve mechanism is the absence of dead centers. The pilot valve formed by the piston I shifts a 20 head of the main valve mechanism and as soon as the piston I begins to connect one set of ports after disconnecting the other set, the resultant change in relative pressures in the opposite ends of the chamber 25 G³ causes the piston I to complete its movement relative to the plunger H, and the fluid pressures acting on it tend to hold the pilot valve I in either end position into which it may be moved. The spring pressed stop 30 collar H¹³ which arrests the upward movement of the piston I is provided to cushion the blow with which the piston engages the collar. While valves G and J operate in regular succession as explained above, their 35 operation is so rapid as to be practically instantaneous.

The spring K when used insures the seating of the valve J at a time when the cylinder chamber C' is connected to the atmosphere, and the pressure in the chamber A' is raised above atmospheric pressure in order to lift the floating anvil and its load for the purpose of compressing the mold, or in the case of a rock over machine for rocking 45 over the mold. To permit the pressure in the chamber A' to be adjusted for this purpose, a valve L² and suitable piping are employed for connecting the chamber A' either to the atmosphere, or to a source of pressure. 50

While in accordance with the provisions of the statutes, I have illustrated and described the best forms of my invention now known to me, it will be apparent to those skilled in the art that changes may be made in the forms of apparatus disclosed without departing from the spirit of my invention, and that under some conditions certain features of my invention may be used 55 without a corresponding use of other features.

Having now described my invention, what I claim as new and desire to secure by Letters Patent, is:

65 1. In a jar molding machine having mold

support and anvil members formed one with a cylinder space and the other with a piston working therein, said mold support being formed with a valve chamber and a port opening therefrom into said cylinder space, 70 the combination with said members of a valve controlling said port, and operating means for said valve located in said chamber.

2. In a jar molding machine having mold support and anvil members formed one with 75 a cylinder space and the other with a piston working therein, said mold support being formed with a valve chamber and a port opening therefrom into said cylinder space, the combination with said members of an 80 apertured inlet valve controlling said port, fluid pressure operating means for said valve including a pilot valve located in said chamber, and a stem passing through the aperture in said inlet valve and adapted to engage 85 the anvil and adjust said pilot valve.

3. In a jar molding machine having mold support and anvil members formed one with a cylinder space and the other with a piston working therein, said mold support being 90 formed with a valve chamber and a port opening therefrom into said cylinder space and said anvil being formed with an exhaust passage leading away from said piston chamber, the combination with said members 95 of an inlet valve controlling said inlet port, an exhaust valve comprising a stem portion passing into said valve chamber, and means located within the valve chamber for bringing about relative movements between said 100 valves.

4. In a jar molding machine having mold support and anvil members formed one with a cylinder space and the other with a piston working therein, said mold support being 105 formed with a valve chamber and a port opening therefrom into said cylinder space and said anvil being formed with an exhaust port leading away from said cylinder space, the combination with said members of an 110 annular inlet valve controlling said inlet port and moving upward into said chamber to open the port, an exhaust valve controlling said exhaust port and comprising a stem portion passing through said annular 115 inlet valve into said valve chamber, and means located within the valve chamber for bringing about relative movements between said valves.

5. In a jar molding machine having mold support and anvil members formed one with a cylinder space and the other with a piston working therein, said mold support being formed with a valve chamber and a port opening therefrom into said cylinder space 120 and said anvil being formed with an exhaust passage leading away from said piston chamber, the combination with said members of an inlet valve controlling said inlet port and moving upward into said chamber 125 130

to open the port, an exhaust valve comprising a stem portion passing through said annular inlet valve into said valve chamber, a piston and cylinder connection between said valves located within the valve chamber, a pilot valve mechanism actuated by relative movements of said mold support and anvil to effect adjustments of said connection and thereby bring about relative movements of approach and separation between said valves.

6. In a jar molding machine having mold support and anvil members formed one with a cylinder space and the other with a piston working therein, said mold support being formed with a valve chamber and a port opening therefrom into said cylinder space and said anvil being formed with an exhaust passage leading away from said piston chamber, the combination with said members of an annular inlet valve controlling said inlet port and moving upward into said chamber to open the port, an exhaust valve comprising a hollow stem portion passing through said annular inlet valve into said valve chamber, a piston and cylinder connection between said valves located within the valve chamber, a pilot valve mechanism also located in said chamber and actuated by relative movements of said mold support and anvil, to govern the admission to the interior of said connection of the exhaust pressure, transmitted through said hollow stem, and the pressure in said chamber to contract and expand said connection.

7. A jar molding machine having mold support and anvil members formed, one with a cylinder space and the other with a piston working therein, and formed, one with a valve chamber and an inlet port opening therefrom to said cylinder space, and the other with an exhaust port leading away from the cylinder space, and in combination therewith, an inlet valve and an exhaust valve controlling said inlet and exhaust ports respectively, a telescopic connection between said valves comprising a cylinder connected to one of said valves and a piston connected to the other of said valves but having a limited movement relative thereto, and ports communicating with the interior of said cylinder and opened and closed by the relative movement of the piston and valve to which it is connected.

8. A jar molding machine having mold support and anvil members formed one with a cylinder space and the other with a piston working therein, and having said mold support formed with a valve chamber, and an inlet port leading therefrom to said cylinder space, and having the anvil formed with an exhaust port coaxial with said inlet port, and in combination therewith, an inlet valve and an exhaust valve controlling said ports, a piston and cylinder connection between

said valves, a pilot valve mechanism adjusted relative to said mold support as the latter approaches the limits of its movement relative to the anvil, and adapted to connect one end of said cylinder to exhaust and the other end to said valve chamber in one position, and to reverse the connections in another position, said pilot mechanism being subjected to the differential of the pressures in the opposite ends of said cylinder and impelled thereby to continue an adjustment started in either direction.

9. A jar molding machine having mold support and anvil parts formed, one with a cylinder space and the other with a piston working therein, and formed, one with a valve chamber and an inlet port opening therefrom to said cylinder space and the other with an exhaust port, and in combination therewith a hollow inlet valve provided with a cylinder extension located within the valve chamber, an exhaust valve having a stem projecting through said inlet valve into the cylinder extension thereof, and a piston working in said extension and mounted on, and adapted to have a limited axial movement with respect to said stem, said stem and piston being formed with ports adapted to connect one end of said cylinder to exhaust and the other to the interior of the valve chamber in one position of said piston relative to said stem, and in another relative position of the stem and piston to reverse said connections.

10. A jar molding machine having mold support and anvil parts formed one with a cylinder space and the other with a piston working therein, and formed one with a valve chamber and an inlet port opening therefrom to said cylinder space, and the other with an exhaust port, and in combination therewith a hollow inlet valve provided with a cylinder extension located within the valve chamber, an exhaust valve having a stem projecting through said inlet valve into said cylinder extension thereof, a piston mounted on said stem and working in said extension and axially movable with respect to said stem, and means restricting the relative axial movement of the stem and piston comprising a resilient buffer restricting relative movement in one direction, said piston and stem being formed with ports adapted to connect one end of said cylinder to exhaust and the other to the interior of the valve chamber in one position of said cylinder relative to said stem, and in another position to reverse the cylinder ends connected to exhaust and valve chamber respectively.

11. A jar molding machine having mold support and anvil members formed, one with a cylinder space and the other with a piston working therein and having said mold support formed with a valve chamber and a port opening therefrom to said space and

having said anvil formed with an exhaust passage, and in combination therewith, a valve mechanism controlling said ports and comprising an inlet valve and exhaust valve 5 and a telescopic connection between said valves, and a yielding abutment normally limiting the upward movement of said valve mechanism relative to said mold support.

12. A jar molding machine having mold support and anvil members formed, one with a cylinder space and the other with a piston working therein, and having said mold support formed with a valve chamber and an inlet port leading therefrom to said cylinder space, and having the anvil formed with an exhaust port coaxial with said inlet port, and in combination therewith, a valve mechanism controlling said ports and comprising a hollow inlet valve, an exhaust valve having a stem projecting upward through the inlet valve into said valve chamber, a piston and cylinder connection between said valves, and a spring opposing the movement of said valve members into their position of closest approach.

13. A jar molding machine having mold support and anvil members formed one with a cylinder space and the other with a piston working therein, and having said mold support formed with a valve chamber and an inlet port leading therefrom to said cylinder space, and having the anvil formed with an exhaust port coaxial with said inlet port, and in combination therewith, a valve mechanism controlling said ports and comprising a hollow inlet valve, an exhaust valve having

a stem projecting upward through the inlet valve into said valve chamber, a piston and cylinder connection between said valves, a spring opposing the movement of said valve members into their position of closest approach, 40 a spring acting between said inlet valve and the mold support tending to hold the inlet valve open, and a yielding abutment normally limiting the upward movement of said inlet valve relative to said mold support. 45

14. A jar molding machine having mold support and anvil members formed one with a cylinder space and the other with a piston working therein, and having said mold support formed with a valve chamber, an inlet port leading therefrom to said cylinder space, and having the anvil formed with an exhaust port coaxial with said inlet port, 50 and in combination therewith, a valve mechanism controlling the said ports and comprising a hollow inlet valve moving upward to open, an exhaust valve having a stem projecting upward through the inlet valve into 55 said valve chamber, a piston and cylinder connection between said valves, a relatively weak spring acting between said inlet valve and the mold support tending to hold the inlet valve open, and a relatively strong 60 spring normally limiting the upward movement of said inlet valve relative to said mold support. 65
